UNITED STATES PATENT OFFICE.

WILLIAM ALLEN HAYWORTH, OF UNIVERSAL, INDIANA.

CAR-COUPING.

1,393,364.

Specification of Letters Patent. Patented Oct. 11, 1921.

Application filed December 18, 1920. Serial No. 431,649.

To all whom it may concern:

Be it known that I, WILLIAM A. HAYWORTH, a citizen of the United States, and resident of Universal, in the county of Vermilion and State of Indiana, have invented 5 certain new and useful Improvements in Car-Couplings, of which the following is a specification.

This invention relates to the construction 10 of car couplers, and more particularly to couplers for use with small rolling stock such as mine cars, lorries and the like.

One object of my invention is the provision 15 of a coupler which is strong and durable, not liable to be accidentally released, and which can be easily, quickly and safely coupled or uncoupled by an operator.

Another object of the invention is to provide 20 a coupler which comprises but two units, thereby providing a single and inexpensive device, with no loose parts to become lost.

These and other objects and advantages 25 of my invention will be brought out hereinafter and illustrated in the drawings forming part of this specification, and in which—

Figure 1 is a top plan of one of the units of my improved coupler.

Fig. 2 is a sectional elevation of the same, 30 the section being taken on the irregular line II—II of Fig. 1.

Fig. 3 is a top plan of the other unit of the coupler.

Fig. 4 is a side elevation thereof.

Fig. 5 is a side elevation, partly in section, 35 of the two coupler units in interlocked or coupled engagement.

In the accompanying drawings the numeral 2 designates the body portion of a forked link forming one of the two units or 40 members of my improved coupler. This link 2 has a rearwardly extending lug 3 which is provided with an eye 4^a to receive the end of the link 4 of a chain by which the coupler unit is fastened to the end of a mine 45 car or the like. The body portion 2 has a transverse cavity or pocket 5 in the upper face thereof, the bottom of this pocket having a hole 5' therein.

The side surfaces 6 and 7 defining the irregular width of the cavity 5 are curved so as to form an undercut recess or pocket, the surface 6 being a compound curve whose curvature is opposite to that of the opposite side surface 7 and the radius of the surface 55 7 is less than that of the upper part of the surface 6. The curvature of the upper part

7' of the wall extends in the same general direction as the upper part of the opposite wall 6. (See Fig. 2).

The front or forward wall 7 is provided 60 with a narrow centrally arranged slot 8 opening at one end into the cavity 5 and having parallel vertical side walls 9 and 10 and a bottom 11 which inclines downwardly at one end (see Fig. 5).

A pair of prongs or fingers 12 and 13, one 65 on each side of the slot 8, project forwardly for an appreciable distance, beyond the bottom 11 of this slot. The adjacent vertical faces of the slot 8 are parallel with the ends 70 of the body 2.

The other unit of the coupler comprises a link having an elongated body or shank 15, the shank having an enlarged rear end 16, which is provided with an eye 16^a that receives 75 the link 16' of the chain used to secure the link to a car. This link also is provided on its upper edge with a grip or handhold 17 that overhangs the forward end of the link (see Fig. 4).

The shank or body 15 is also provided intermediate its ends with a pair of cylindrical bearing pins or projections 18, one on each side thereof, which are adapted to support the fingers or prongs 12 and 13 of the 80 recessed unit 2 when the two units or members are assembled in interlocking engagement.

A second pair of cylindrical pins or projections 19 are integrally formed with, and 85 adjacent the forward lower edge of the shank 15, the corner 20 of the shank being rounded off to correspond with the curvature of the projections 19. The projections 19 are adapted to fit into the recess or cavity 90 5 and to engage in the curve of the undercut wall 7 thereof.

A projecting flange 22 extends outwardly from each side of the shank 15 and extends forwardly beyond the end of the shank 15 100 to the front end of the overhanging grip or handhold 17. The projections 22 are of sufficient width to extend beyond the ends of the cavity 5 and overlie the surrounding walls of the body portion 2 of the forked 105 link.

The operation of my improved coupler will be readily understood. When it is desired to disengage or uncouple the interlocked links, (which are shown in coupled 110 or interlocking position in Fig. 5), the links are lifted by grasping the handhold 17.

There, of course, will be enough slack in the chains 4 and 16' to permit of the links lifting freely. Such lifting movement causes the tongues 12 and 13 of the forked link 2 to slide on the projections 18 on each side of the other link and the pins 19-19 to lift until out of the cavity or pocket 5. When the pins 19-19 are clear of the cavity or pocket 5, the forked link will be disengaged 10 from the opposite link and will drop, and the other link is then allowed to fall.

In connecting the links to couple two cars the links are lifted until in practically vertical lengthwise position. The shank 15 is 15 then slipped into the slot 8 of the forked link 2 and the fingers 12 and 13 brought into engagement with the pins 18. The two links are then lowered until the pins 19 rest in the cavity 5 of the forked link 2 and the wings 20 or flanges 22 engage the upper faces of the link 2. The coupler will then again be in the interlocked position shown in Fig. 5.

The above described operations will be repeated from time to time in uncoupling 25 and coupling the links.

The advantages of my invention which will be appreciated by those skilled in the art arise from the compact construction and absence of swinging and removable parts.

30 Various modifications, as will suggest themselves to those skilled in the art, may be made in the construction of my improved coupler without departing from the spirit of the invention as defined in the appointed 35 claims.

I claim:

1. A car coupler comprising in combination separable links arranged to coact in interlocking engagement one with the other 40 and having means for attachment thereof to the cars, one link having a cavity therein and having fingers on one end thereof, and the other link having projecting pins on opposite sides thereof, arranged to enter 45 said cavity and other projecting pins arranged to engage the under surface of said fingers in securing the links in interlocking engagement.

2. A car coupler comprising in combination separable links arranged to coact one with the other, means whereby said links are flexibly connected to the cars, one link 50 having a recess forming an undercut in its upper face and having projecting fingers 55 forming a slot on one end thereof, and the other link having projecting pins on opposite sides thereof adapted to enter said undercut cavity and other projecting pins arranged for engagement with said fingers in 60 connecting the links in interlocking engagement, and one end of said second link extending into the slot formed by the fingers on the recessed link.

3. A car coupler comprising a forked link 65 and coacting link, said forked link having a

cavity in the upper face thereof and being slotted longitudinally, said coacting link having cylindrical projections on the sides thereof adjacent its forward end adapted to enter said cavity in said forked link, and 70 means for supporting the forward end of said coacting link on said forked link.

4. A car coupler comprising in combination separable links arranged to coact in interlocking engagement one with the other 75 and having means for attachment thereof to the cars, one link having a cavity therein and having fingers on one end thereof and the other link having projecting pins on opposite sides thereof, some of said pins being 80 arranged to enter said cavity and other of said pins being arranged to engage the under surface of said fingers in securing the links in interlocking engagement, and means on one end of one link forming a handhold 85 for manipulating said links.

5. A car coupler comprising in combination separable links arranged to coact in interlocking engagement one with the other and having means for attachment thereof to 90 the cars, one link having a cavity therein and having fingers on one end thereof and the other link having projecting pins on opposite sides thereof, some of said pins being 95 arranged to enter said cavity and other of said pins being arranged to engage the under surface of said fingers in securing the links in interlocking engagement, and means on one end of one link forming a handhold for manipulating said links and lugs on the 100 sides of the second link forming flanges engaging the upper surface of said forked link in connecting the links in coupled relation.

6. A car coupler comprising in combination separable links arranged to coact in interlocking engagement one with the other and having means for attachment thereof to the cars, one link having a cavity therein and having fingers on one end thereof and the other link having projecting pins on opposite sides thereof, some of said pins being 110 arranged to enter said cavity and other of said pins being arranged to engage the under surface of said fingers in securing the links in interlocking engagement, and means on one end of one link forming a handhold for manipulating said links and lugs on the sides of the second link forming flanges 115 engaging the upper surface of said forked link in connecting the links in coupled relation, and an extension on the flanged end of said other link forming a handhold for manipulating said links.

7. A car coupler comprising, in combination a forked coupler link and a coacting link, said links being adapted to be interlocked, said forked link comprising a body portion terminating at its forward end in a 125 pair of fingers and having a cavity in its 130

- upper face provided with a concave wall, said second link comprising a body portion having supporting projections on opposite sides thereof and intermediate its ends, said 5 projections being adapted to underlie and support the fingers of said forked link, cylindrical projections on each side of said second link at the forward end thereof, extending outward therefrom, said projections being adapted to fit into the cavity in said 10 forked link, flanges forming shoulders on said second link adapted to overlie the cavity in said forked link and engage the body thereof, and a hand-hold on said second 15 link.
8. A car coupler comprising a forked link and a coacting link adapted to be interlocked, said forked link having a cavity in the upper face thereof, said coacting link having a pair of projections on the sides 20 thereof adapted to enter and interlock with the cavity in said forked link, and means for preventing said links breaking downwardly beyond a horizontal plane when interlocked.

In testimony whereof I have hereunto 25 signed my name.

WILLIAM ALLEN HAYWORTH.
